UNITED STATES PATENT OFFICE.

WILLIAM L. PAUL, OF BERKELEY, CALIFORNIA, ASSIGNOR TO DEERE AND COMPANY,
OF MOLINE, ILLINOIS, A CORPORATION OF ILLINOIS.

CULTIVATOR.

Application filed April 25, 1916, Serial No. 93,402. Renewed July 12, 1923.

My invention relates to tillage machines and more particularly to the type known as two row cultivators, and the object of my invention relates to the lateral adjustment 5 of the gangs of cultivating devices and to certain means employed to guide the machine by angling the supporting wheels, as will be more clearly set forth in the following specification.

10 Referring to the drawings in which similar numerals indicate identical parts—

Figure 1 is a plan view of a two-row cultivator having my improvements embodied therein. Figure 2 is a side elevation with 15 the wheels removed. Figure 3 is a front elevation of one end of the machine. Figure 4 is a rear elevation of part of the machine. Figure 5 is a plan view of part of the cultivator showing in dotted lines the position of 20 the main frame when the wheels are angled. Figure 6 is a detail side elevation of the gang beam adjusting lever and connected parts. Figure 7 is a detail plan view of the bell cranks by which the gangs are adjusted 25 laterally. Figure 8 is a sectional detail of part of the support of the forward end of a gang beam. Figure 9 is a detail plan of one of the master levers and connections, and Figure 10 is a side elevation thereof.

30 A main frame consists preferably of two channel bars 1 and 2 having their ends curved and joined and secured firmly together by castings 3 bolted to both bars. Integral with the castings 3 are sleeves 4 forming bearings 35 in which are journaled vertical spindles 5 forming part of crank axles 6 which are bent to extend rearwardly from the spindles 5 and are then bent outwardly to form horizontal spindles 7 on which are mounted supporting wheels 8. Rigidly secured centrally 40 on the main frame is a seat support 9 composed preferably of two flat parallel bars spaced apart and extended forwardly of the main frame to form a supporting means for 45 a draft device. On the rear of the support 9 is fixed a seat 10.

On the upper ends of the spindles 5 are rigidly secured rearwardly extending arms 11 connected with each other by a transverse 50 rod 12; centrally on the rod 12 is secured a casting 13; between the bars of the seat support 9, adjacent the frame bar 2, is a casting 14 in which is journaled the central vertical portion of a crank member 15 which is bent 55 rearwardly above and below the casting 14,

the upper rearwardly extending portion having a vertical termination which is journaled in the casting 13 on the rod 12.

The lower rearward extension of the crank member 15 has preferably integral therewith 60 laterally extending arms 16 on the free ends of which are secured foot rests or treadles 17.

The gang beams are supported on the frame 1 in the following manner; the beams are constructed of bars 19 and 20 spaced 65 apart at their rear by braces 21 bolted thereto, and converge forwardly to couplings 22 to which they are secured. The gang beams are arranged in pairs and are connected to and spaced apart by vertically disposed yokes 70 23 and 23^a having their free ends bent horizontally and inserted in bearings 24, integral preferably with the couplings 22. The bearings 24 are cut away for part of their length 75 to permit collars 25 to be mounted on the horizontal ends of the yokes 23 and secured thereon by set screws 26; V. shaped supports 27 are journaled in bearings 28 on the collars 25 and have their free ends bent inwardly 80 and inserted in suitable openings in the bars 80 1 and 2.

A lever 29 is pivotally mounted intermediate its ends on the seat support 9 and is provided with the usual type of latch to engage with a toothed semi-circular rack 30 secured 85 on the seat support 9. Bell cranks 31 and 32 are pivotally supported one above the other by a vertical pivot 33 on a casting 34 secured on the seat support 9; a link 35 is pivotally secured to the lever 29 above the pivot thereof and extends forwardly, its forward end being bent into a hook which engages with a suitable perforation in an arm 36 projecting laterally from the bell crank 31 and preferably integral therewith; a similar link 37 90 is pivotally secured to the lower extremity of the lever 29 and extends forwardly to connection with a laterally extending arm 38 on the bell crank 32 and extending in the same direction and parallel with the arm 36. 95

On the inner vertical portion of the yoke 23 is rigidly secured a member 39 having an eye in which is hooked an end of a link 39; the link 39 extends inward and is connected to a forwardly projecting arm 40 of the bell crank 31. A similar member is rigidly secured on the inner vertical portion of the yoke 23^a and is provided with an eye in which is hooked an end of a link 41 which 100 extends inward and is connected to a for- 110

wardly projecting arm 42 of the bell crank 32.

To raise and lower the gang beams, on which I have shown cultivating shovels of a well known type, I employ the following mechanism: The gang beams are arranged in pairs and each pair is vertically adjustable independently of the other, and by similar means, a description of the raising mechanism of one gang will suffice. Mounted in bearings 43 and 44 on the frame bar 1 is a rock shaft 45 having rearwardly extending arms 46 and 47. A similar rock shaft 48 is journaled in a bearing 49, also mounted on the frame bar 1, and provided with rearwardly projecting arms 50 and 51. Mounted on the gang beams are brackets 52 to which are connected links 53 and 54 extending upwardly and pivotally attached to the arms 46 and 50 respectively. A lever 55 is rigidly secured to the arm 47 and a master lever 56 is rigidly secured to the arm 51; on the master lever 56 is a notched segment 57 with which a well known type of latch on the lever 55 is adapted to engage, and secured on the frame bars 1 and 2 is a notched segment 58 with which a latch on the master lever 56 is adapted to engage.

Connected to the links 53 and 54 near their lower ends are coiled balancing springs 59 which are also connected to the arms 46 and 50 of the rock shafts 45 and 48 respectively. The links 53 and 54 are spaced apart by a yoke formed of members 60 and 61 pivotally connected to the links 53 and 54, and bent laterally to overlap, they are secured together by bolts or cotters inserted in suitable perforations in both members. In this mechanism just described it will be seen that the outer gang beam can be raised independently of the inner gang beam by operation of the lever 55 after the latch thereon is disengaged from the segment 57, and it is also apparent that both gang beams can be raised simultaneously when the master lever 56 is freed from the segment 58 and operated, the lever 55 being held on the segment 57 on the master lever 56, or the inner gang beam can be raised independently of the other by disengaging both levers from their respective segments and operating the master lever 56.

As previously described the wheels 8 are supported on the axles so as to have their axis rearward of the main frame. This arrangement results in a very material advantage when the wheels are angled to right or left to change the direction of travel of the machine necessitated by unevenness of the rows of plants being cultivated, and this advantage consists in that when the wheels are angled the frame and the gang beams connected therewith are moved transversely of the machine toward the normal longitudinal vertical planes of the wheels, and

in the direction toward which the wheels are turned as shown in dotted lines in Figure 5, it being evident that pressure upon the treadles 17 will actuate the crank member 15 to move the rod 12 laterally, and as the rod 12 is connected to the arms 11, secured rigidly to the upper ends of the spindles 5, the crank axles 6 are oscillated and the wheels are angled to right or left as may be desired, the frame and attached gangs moving simultaneously therewith.

The operation of angling the wheels 8 and simultaneously imparting a lateral movement to the main frame and gang beams does not prevent independent lateral adjustment of the gang beams, for by actuation of the lever 29 forwardly the bell cranks 31 and 32 are operated by the rods 35 and 37, and through the connection of the yokes 23 and 23^a to the bell cranks 31 and 32 by the rods 39 and 41, the yokes 23 and 23^a are moved toward each other to bring the gang beams, and cultivating devices thereon, closer together for close cultivation. A rearward actuation of the lever 29 will move the yokes 23 and 23^a further apart carrying with them the gang beams and cultivating devices, as will be readily understood. When the lever 29 is in a vertical position, as shown in the drawings, the parts are in position for ordinary cultivation, but rocking the lever 29 either way from the vertical adjusts the cultivating devices for rows of different distances apart, the gang beams swinging on the V shaped supports 27 by which they are supported on the main frame.

The lateral movement of the main frame it is evident does not interfere in any way with proper adjustment of the cultivating devices.

What I claim is—

1. A cultivator having a frame, axles having vertical spindles rotatably journaled on the frame, an extension from each spindle, supporting wheels on said extensions, a seat support fixedly mounted on said frame, tool gangs connected with said frame, and means mounted on said frame and operable to move the frame and the tool gangs simultaneously laterally relatively to the wheels.

2. A cultivator having a frame, axles having vertical spindles rotatably journaled on the frame, an extension from each spindle, supporting wheels on said extensions, a seat support fixedly mounted on said frame, laterally rigid tool gangs connected with said frame, means mounted on said frame and operable to move the frame and the tool gangs simultaneously laterally relatively to the wheels, and separately operable means for moving the tool gangs bodily laterally relatively to the frame.

3. A cultivator having a frame, axles having vertical spindles rotatably journaled on

- the frame, an extension from each spindle, a supporting wheel journaled on a horizontal spindle on each extension, a seat support fixedly mounted on said frame, tool gangs connected with said frame, and means mounted on said frame and operable to move the frame laterally relatively to the wheels and simultaneously angulate the wheel spindles relatively to the line of advance. 5
- 10 4. A cultivator having a frame, axles having vertical spindles rotatably journaled on the frame, an extension from each spindle, a supporting wheel journaled on a horizontal spindle on each extension, a seat support fixedly mounted on said frame, laterally rigid tool gangs connected with said frame, means mounted on said frame and operable to move the frame laterally relatively to the wheels and simultaneously angulate the wheel spindles relatively to the line of advance, and separately operable means for moving the tool gangs bodily laterally relatively to the frame and the wheel spindles. 15
- 20 5. A cultivator having a frame, axles having vertical spindles journaled on the frame, said axles extending rearward from the spindles, supporting wheels on the rearward extensions, a seat support rigidly mounted on said frame, a crank member on the seat support, and means connecting said crank member with the axles and adapted to be actuated by the swinging of said crank member to swing said axles to adjust the wheels angularly to the line of draft, and to move said frame and seat support laterally in the same direction simultaneously with the wheel adjustment. 25
- 30 6. A cultivator having a frame, axles having vertical spindles journaled on the frame, said axles extending rearward from the spindles, supporting wheels on the rearward extensions, a plurality of cultivating devices connected with said frame, a seat support rigidly mounted on said frame, a crank member on the seat support, and means connecting said crank member with the axles and adapted to be actuated by the swinging of said crank member to swing said axles to adjust the wheels angularly to the line of draft, and to move said seat support and frame and cultivating devices laterally in the same direction as the wheel adjustment 40
- 45 50 55 60 65
7. A cultivator having a frame, axles having vertical spindles journaled on the frame, said axles extending rearward from the spindles, supporting wheels on the rearward extensions, a plurality of cultivating devices connected with said frame, a seat support rigidly mounted on said frame, a crank member on the seat support, means connecting said crank member with the axles and adapted to be actuated by the swinging of said
- crank member to swing said axles and adjust the wheels angularly to the line of draft and to move said seat support and frame and cultivating devices bodily and laterally in the same direction as the wheel adjustment 70
8. In a cultivator having a frame, axles having vertical spindles journaled on the frame, said axles extending rearwardly of the frame and having supporting wheels on their rearward ends, rearwardly extending arms rigidly secured to said spindles, a seat support rigidly mounted on the frame, a crank member on the seat support, and means connecting said crank member with said arms and adapted to be actuated by the swinging of said crank to swing said axles to adjust the wheels angularly to the line of draft, and to move said seat support and frame and spindles bodily and laterally in the same direction as the wheel adjustment 75
- 85 90 95 100 105
9. In a cultivator having a frame, rearwardly extending axles journaled thereon to swing laterally, supporting wheels on the rearward ends of said axles, arches supported on the frame at each side of the center thereof, gangs of cultivating devices connected with said arches, a seat support rigidly mounted on said frame, a crank member on the seat support, and means connecting said crank member with the axles and operable by the swinging of said crank member to swing said axles and wheels angularly to the line of draft, and to move said frame and arches and gangs of cultivating devices bodily in the same direction as the wheel adjustment 110
- 115 120 125 130
10. In a cultivator, the combination of a frame, rearwardly extending axles journaled thereon to swing laterally, supporting wheels on the rearward ends of said axle, arches supported on the frame at each side of the center thereof, gangs of cultivating devices connected with said arches, a seat support rigidly mounted on said frame, and a crank member operatively connected with said frame to turn about an upright axis and operable to swing the axles and wheels angularly relatively to the line of draft, and to move said frame, arches and gangs of cultivating devices bodily in the same direction as the wheel adjustment 120
- 125 130
11. A cultivator having a frame, axles having vertical spindles journaled on the frame, said axles extending rearward from the spindles, supporting wheels on the rearward extensions, a plurality of cultivating devices connected with said frame, a seat support rigidly mounted on said frame, a crank member pivoted on the seat support

and having laterally extending arms, a rod connecting said crank member with the axles, treadles on the free ends of said arms by which the crank member is actuated to swing 5 the axles to adjust the supporting wheels angularly to the line of draft and to simultaneously move the frame, spindles and cultivating devices bodily in the same direction as the wheel adjustment, bell cranks pivotally mounted on the seat support and con-

nected with the cultivating devices, and a lever pivoted on said frame and connected to said bell cranks and operable to adjust the cultivating devices laterally independently of their movement by the wheel adjustment. ¹⁵

In testimony whereof I affix my signature.

WILLIAM L. PAUL.
